RECEIVING APPARATUS

Wilhelm Runge, Berlin, Germany, assignor to
Telefunken Gesellschaft für Drahtlose Tele-
graphie m. b. H., Berlin, Germany, a corpora-
tion of Germany

Application July 8, 1930, Serial No. 466,427
In Germany August 20, 1929

5 Claims. (Cl. 250—8)

When modulating (keying) the amplitude of a shortwave transmitter in the usual way, it is frequently noticed at the receiving end that the signals seem extended, indeed, the signals are longer and the spaces shorter than what has been sent out. Extensive investigations have shown that the beginning of the signal is always faithfully transmitted, but that after the completion of the transmitted signal additional energy arrives which presumably reaches the receiving station from the transmitter in a roundabout way and thus takes more time in arriving. If it is important to insure the correct length of the transmitted signals as is necessary, for instance, in picture telegraphy, then the signals must be chosen of greater length compared with the "reverberation" period in order that the latter may not become apparent. But this limits the rate of telegraphing.

To increase the working speed it has been suggested to modify the frequency of the transmitter in such a way that during the time the signal is transmitted one frequency is radiated off from the antenna, while during spaces a different frequency is radiated. The receiver must then be so conditioned that it will record only the beginnings of the wave-trains of each frequency. The signals will then be transmitted of the proper length independently of the reverberation period.

Receivers adapted to pick up detuned signals are known in the prior art. In what follows a receiving apparatus shall be disclosed which responds only to the beginning of incoming wave-trains and which makes a record of the signal from its beginning and the beginning of the space.

In the drawing, Fig. 1 shows the receiver arrangement, and Fig. 2 shows curves explanatory of the operation of the receiver.

The receiving means 1 and 2 of Fig. 1 comprise suitable signal absorption and rectifying devices and filter amplifiers adapted to separate the two frequencies f_1 and f_2 from each other. According to this invention the signals of both frequencies are then separately rectified in rectifiers 3 and 4 connected with receivers 1 and 2 respectively, while after rectification they are fed to two transformers 5 and 6 whose impedance 50 for the value

$$\frac{di}{dt}$$

for the beginning of the rectified signals is not small compared with the internal resistance of rectifiers 3 and 4. The output terminals of transformers 5 and 6 are associated with the grids of two additional tubes 7 and 8, and these are biased from biasing batteries 9 and

10 to an extent so that no plate current flows in the tubes when no signal is received.

The polarity of the transformers is so chosen that a growth of current in the primary winding results in positive charging of the grid connected to the secondary winding. When a signal of frequency f_1 reaches the receiver apparatus, a current starts to flow through the rectifier; while this current grows, a potential arises across the secondary winding of the transformer 5 whereby the action of biasing potential 9 is decreased. Hence, tube 7 furnishes a current. After the signal has been built up to its full value, the potential across transformer 5 collapses, and when the signal is terminated there arises there a potential unidirectional with battery 9. Hence, it is only at the beginning of the signal of frequency f_1 that tube 7 supplies a rush or impulse of current independently of the length of the signal. And in a similar way tube 8 furnishes an impulse of current only at the beginning of the signal of frequency f_2 .

Connecting the tubes 7 and 8 with a relay comprising auxiliary sources of current or a similar device 11 in such a manner that an impulse from tube 7 shifts the relay in one position, and an impulse from tube 8 in the other direction, then currents will be derived from terminals 12, 13 which correspond to the signals to be transmitted without the latter being altered by "reverberation" phenomena; and the ensuing currents can be further treated and used by recording apparatus of a kind well known in the prior art.

The output current of an arrangement as hereinbefore disclosed is not altered in any way if the transmitter, instead of radiating for signals one frequency, and during the spaces the other frequency, is made to send out short impulses of one frequency only at the beginning of signals, and impulses of the other frequency at the beginning of the spaces, seeing that the output current of the arrangement here disclosed depends solely upon the instant of the beginning, and not upon the duration or length of the signal in question.

The whole process is schematically illustrated in the following manner (see Fig. 2):

I is the signal to be transmitted.

II amplitude of the incoming signals sent on frequency f_1 .

III amplitude of signals sent on frequency f_2 .

IV potential across terminals of transformer 5.

V potential across terminals of transformer 6.

VI and VII current from tubes 7, 8 respectively.

VIII current from terminals 12, 13.

Since the "reverberation" phenomena occasionally are not embraced by a smooth envelop, but present peaks occasioned by undesirable potentials across transformers 5 and 6, it is recommendable to dispose means on either side of trans-

formers 5 and 6 which are permeable to signal frequencies, though impermeable for higher frequencies; or else the transformers themselves may be built so as to fulfill the identical end, as shown in Fig. 1 by capacities 14, 15, 16, 17.

It may also be of advantage to so regulate the amplification factor that the amplification is greatly diminished upon the arrival of a signal while caused to rapidly grow after termination 10 of a signal, the rate of growth being so chosen that after the "reverberation" period the sensitivity resumes its former value.

This normal amplification value in turn may be so controlled by the amplitude of the incoming 15 signals that at such times when the signals come in very strong the amplification is made correspondingly small, and vice versa, so that the maximum value of the currents leaving rectifiers 20 3 and 4 will turn out roughly constant independently of the strength of the incoming signals.

I claim:—

1. The method of producing currents truly representative in electrical length to the marking and spacing impulses sent out at different frequencies by a transmitting system which includes the steps of, separately receiving said marking and spacing frequencies, rectifying each of said received frequencies to produce unidirectional current impulses, and producing by means of said 25 unidirectional impulses a current flow whose initiation is simultaneous with inception of said impulses but whose duration is independent of the length of said impulses.

2. Means for receiving signals from a transmitter which sends out oscillations of one frequency for marking and oscillations of another frequency for spacing and for producing representations of time duration equal to the duration of the marking and spacing oscillations including, a separate receiving means for each of said frequencies, a rectifying means connected with each receiving means, a thermionic relay tube for each rectifying means, a transformer for each thermionic relay tube, each of said transformers having its primary winding connected with one of said rectifiers and its secondary winding connected with one of said relay tubes, a condenser connected in parallel to the secondary winding of each of said transformers, means for applying a constant biasing potential to the input electrodes of each of said thermionic relay tubes,

which biasing potential opposes the bias applied thereto when current flows in the secondary winding connected therewith, and marking means connected with the output electrode of each of said relay tubes.

3. The method of producing currents truly representative in electrical length of the marking and spacing impulses sent out at different frequencies by a transmitting system which includes the steps of separately receiving said marking and spacing frequencies, rectifying each of said frequencies to produce unidirectional current impulses, utilizing the steep wave front only of the beginning of said unidirectional impulses to produce a current flow whose initiation is approximately simultaneous with the inception of said unidirectional impulses, but whose duration is shorter than the duration of said impulses.

4. The method of producing currents truly representative in electrical length of the marking and spacing impulses sent out at different frequencies by a transmitting system which includes the steps of separately receiving said marking and spacing frequencies rectifying each of said received frequencies to produce unidirectional 20 current impulses, obtaining from each unidirectional impulse two sharp pulses of different polarities whose durations are independent of the length of said impulses, and utilizing only those sharp impulses of a predetermined polarity to 25 record the signal energy.

5. In a radio signaling system, the method of producing currents truly representative in electrical length of the marking and spacing impulses sent out at different frequencies by a transmitting system which includes the steps of separately receiving said marking and spacing frequencies, rectifying each of said received frequencies to produce unidirectional current impulses, obtaining from each unidirectional current impulse at 30 the approximate inception thereof a sharp pulse of a predetermined polarity whose duration is independent of the length of said impulses, modifying said sharp pulses, and utilizing said sharp 35 pulses of predetermined polarity to record the signal energy, the sharp pulses obtained from rectifying the marking frequencies recording the signal energy differently from those obtained from rectifying the spacing frequencies.

WILHELM RUNGE.
